UNITED STATES PATENT OFFICE.

JOSEPH E. BADGER, MAX K. GOLDEN, AND VICTOR K. GOLDEN, OF DETROIT, MICHIGAN, ASSIGNORS TO TEXTILE PRODUCTS COMPANY, OF DETROIT, MICHIGAN, A CORPORATION OF MICHIGAN.

TUBULAR FABRIC.

Application filed September 20, 1923. Serial No. 663,781.

To all whom it may concern:

Be it known that we, JOSEPH E. BADGER, a British subject, and MAX K. GOLDEN and VICTOR K. GOLDEN, citizens of the United States, residing at Detroit, county of Wayne, State of Michigan, have invented a certain new and useful Improvement in Tubular Fabrics, and declare the following to be a full, clear, and exact description of the same, such as will enable others skilled in the art to which it pertains to make and use the same, reference being had to the accompanying drawings, which form a part of this specification.

Our invention relates to a tubular fabric and the manufacture of same for constructing hats or other article of apparel.

The primary object of this invention is to provide a tubular braid formed of strips of plush, silk or other suitable material with a lining of relatively stiff fabric as for example buckram, haircloth, or other material of like nature, enclosed within the outer fabric to insure the latter against collapsing when sewed together to form the crown and brim of a hat or other article of apparel.

In the drawings accompanying this specification:

Figure 1 is an elevation of the tubular braid fabric showing the abutting edges of the outer strip sewed together and overlapping a lining strip of buckram or like stiff material enclosed within the outer fabric.

Figure 2 is a cross-sectional view through the same.

Figure 3 is a diagrammatical perspective view showing a strip of plush or other suitable fabric and a lining of buckram or other "stiffening" material as it is shaped into tubular form in its passage through a suitable guide member adapted to cause the edges of the outer fabric to overlap the edges of the lining;—showing the abutting edges of the outer fabric sewed together by means, (not shown, but well understood in the sewing machine art) as it leaves the guide member.

Figure 4 represents a woman's hat constructed of the tubular braid, sewed together to form the body and brim.

Referring now to the letters of reference placed upon the drawings:

A, represents a strip of plush, silk or other fabric. B, indicates a narrow strip of buckram enclosed within the outer fabric:—the edges A¹ of the latter being bent to overlap the edges of the lining by a suitable guide C, as it passes through the latter. D, denotes a line of stitching securing the abutting edges of the outer fabric together to form a tubular braid.

Having thus described our invention what we claim is:

1. As an article of manufacture, a tube for the production of hats comprising an inner and an outer layer of material folded one within the other to form a tube, the inner layer being composed of stiff material to render the tube stiff and prevent collapsing of the outer layer, the longitudinal edges of the outer layer overlapping the longitudinal edges of the inner layer and a line of stitching connecting the abutting edges of the outer layer together.

2. The method of producing a tube for the manufacture of hats which consists in placing two layers of material in superimposed relation, the inner layer being narrower than the outer layer and stiff, passing the superimposed layers through a guide to simultaneously force the longitudinal edges of the outer layer into overlapping relation with the longitudinal edges of the inner layer and to fold the layers into non-collapsible tubular form and sewing the abutting edges of the layers together.

In testimony whereof, we sign this specification in the presence of two witnesses.

JOSEPH E. BADGER.
MAX K. GOLDEN.
VICTOR K. GOLDEN.

Witnesses:

MAURICE WOLF,
S. E. THOMAS.
